SANDBLAST NOZZLE

Frederick W. Schultz, Wichita, Kans.

Application December 23, 1935, Serial No. 55,826

6 Claims. (Cl. 51—11)

My invention relates to a sand blast nozzle adapted to use a limited amount of air and sand in conjunction with a predetermined amount of water or moisture whereby the sanding operations may be accomplished in a minimum period of time, while the objectionable hazard encountered in sand blasting operations will be materially reduced, if not entirely eliminated.

The invention has for its object the construction wherein the sand will be broken up into finer particles or grains and a proper mixing of the moisture or water with said sand accomplished before the sand is discharged.

Another object of my invention is to provide a nozzle of the type in question wherein the wear receiving portions of the discharge end or mouth of the nozzle are removably secured in place in order that renewal or replacement of such parts may be accomplished.

The objects and advantages of my invention will be readily comprehended from the following detailed description of the embodiment disclosed in the accompanying drawing, wherein:—

Figure 1 is a side elevation of my improved nozzle with a portion of the side wall broken away to disclose interior construction.

Figure 2 is a longitudinal sectional view taken substantially on the line 2—2 of Figure 1, as viewed by the arrows.

Figure 3 is an end elevation as viewed from the discharge end or mouth.

Figure 4 is a cross sectional view taken substantially on the line 4—4 of Figure 2, looking in the direction of the arrows.

Figure 5 is a detail perspective view of one of the discharge end plates with a portion broken away.

Figure 6 is a similar view of one of the filler or spacer plates.

The specific embodiment of my invention, as disclosed in the drawing, involves certain improvements on the type of sand blast nozzle disclosed in my copending application Serial Number 19,371 and is especially adapted for sand blasting surfaces where scoring would be objectionable and where the element of time and material is also essential.

The body of the nozzle preferably consists of an elongated and somewhat cylindrical casing 15 of prearranged and convenient proportions and reduced somewhat at one end to provide the tubular nipple or collar portion 16 which is preferably internally threaded to receive the usual hose gripping bushing and inlet nozzle which are not

shown but which may be of the type shown in my previous application referred to. The other or discharge end of the casing is more or less flattened out so as to provide the two tapering sides 17, 17 as shown in Figure 1, while the portions intermediate of these tapering sides are spread or built out laterally to provide the laterally disposed ear or wing portions 18, 18, see Figure 3.

That is to say, there are two wing portions 18 on each side which, at the end and for a short distance removed from the end, are spaced from each other to receive a pair of hardened steel plates 19 of predetermined width and of length to extend across the outlet of the nozzle to form the mouth or nozzle tip; and these plates are maintained in spaced parallel relation with each other by suitable filter plates or spacers 20. The construction of these plates 19 and 20 is shown in detail in Figures 5 and 6.

The filter plates 20, like plates 19, are of hardened steel; the plates 20 being arranged intermediate of the ends of the two plates 19 at opposite sides of the discharge end or mouth of the nozzle and are comparatively narrow so as to provide an elongated substantially straight lined narrow discharge opening 21.

The outer ends of the wing portions 18, the ends of the tip plates 19 and the spacer or filter plates 20 are all apertured to receive bolts 22, so that when the nuts 23 are screwed up on the bolts 22 the ears or wing portions will be drawn into tight relation with the tip plates 19 and the latter drawn into tighter relation with the filter plates 20; the ends of the tip plates 19 and of the spacer or filter plates 20 closing the spacing at the sides of the discharge mouth of the nozzle intermediate of the ears or wing portions 18 so that air or sand cannot find egress at the sides of the nozzle-mouth.

In order to enable a proper shaping of the nozzle body and also provide access to the interior during construction, the opposite sides in alignment with the spacing between the ears 18 is slit to receive the radially disposed webs 24 whose inner ends are intimately secured or welded to the collar or pipe coupling member 25 arranged concentrically within the tubular body 15.

This coupling 25 is interiorly threaded to receive the externally threaded end of a short pipe or tubular member 26 and to maintain the latter in concentric relation with the casing 15 and to provide a comparatively large annular passage 55

about the member 26, as clearly shown in Figures 2 and 4.

The opposite end of the coupling is provided with a steel plug 27 which is tightly driven into the coupling and welded in place and the forward or inner face of the plug 27 is preferably provided with a hardened bronze covering, indicated at 28, adapted to withstand greater wear; while the short tubular member or nipple 26 is preferably case hardened to withstand the action of the incoming sand introduced through the nipple end 16 by means of a suitable nozzle as for example shown in my co-pending application.

In operation the tubular member 26, whose open end is in alignment with the incoming sand under pressure, is adapted to receive the sand and to fill up, thereby providing an impact receiving pocket; the sand after overflowing being forced around the tubular member 26 and past the webs 24, toward the discharge end of the nozzle.

With the plates 19 extending a distance into the casing 15 it is apparent that a sand arresting pocket is provided above the upper plate and beneath the lower plate when the nozzle is positioned as viewed in Figure 1.

These pockets at the discharge end like the concentric pocket 26 soon become filled with sand thereby providing a striking bed for the incoming stream of sand to strike against. The incoming sand is introduced directly in line with the open end of the tubular member 26, causing the sand to more or less combat itself and to set up a vigorous action which causes the sand to break up into a very much finer state than when it entered the nozzle. The turbulent action set up by the arresting pocket member 26 tends to choke the air and to distribute the sand equally throughout the casing and thus diminish its severity. The turbulent sand coming from the arresting pocket 26 has a tendency to follow the sloping walls of the casing and to set up somewhat of a cross fire a short distance from the discharge orifice thereby tending to somewhat further diminish the striking force of the discharging sand.

The casing 15 at a point preferably coincident with an intermediate part of arresting pocket 26 is shown provided with an L-nipple or elbow tube 29 which is preferably welded into a hole in the casing 15 by means of bronze as at 30. As is apparent, water may thus be admitted into the casing 15 at a point intermediate of the ends of the arresting pocket 26 so that the water encounters the sand after its breaking-up action in pocket 26; the water being made to commingle with the fine sand passing about the pocket 26. The air and sand in addition to entraining the water tend to convert the water into a mist.

With a proper regulation of the ingoing sand a lesser amount of sand may be used and the moistened broken-up sand provides a somewhat faster cutting action than when dry. Furthermore, the water mist also eliminates the dust that otherwise would result during a dry sanding operation. This also permits sanding operations to be performed within an enclosure. With my improved nozzle, if it is desired to wash any parts or objects that have been sanded, the inflowing sand stream may be shut off and merely the air and water allowed to enter thereby quickly providing a spraying nozzle.

It has been found in practice that the sand is broken up so fine that the nozzle may be used for a great many purposes where the conventional method of sanding would be much slower

and a special fine sand would have to be prepared; my improved nozzle making it possible to sand comparatively delicate surfaces.

In practice it is found that most of the wear is encountered by the plates at the discharge orifice and with my improved construction these plates when worn can be readily removed and replaced thus enhancing the life of the nozzle and consequently materially reducing replacement cost.

With the comparatively wide plates 19 the nozzle is provided with a narrow straight throat or mouth which causes the sand to discharge in a substantially straight line and with a strong striking force.

It will be understood, of course, that the size of the discharge orifice may vary in keeping with the size of the main casing, a certain relation being preferable to obtain the sand action within the casing.

The construction shown and described is believed to be the best embodiment of my invention, but modifications are possible and may be made without departing from the spirit of my invention.

What I claim is:

1. A sand blast nozzle of the character described comprising an elongated casing having a sand and air inlet at one end and a discharge at the opposite end, the discharge end of the casing being gradually reduced so as to taper on two opposite sides and to flare outwardly on two opposite sides and said flared sides slit for a predetermined distance to provide a pair of laterally disposed ears on both of said flared sides; flat plates arranged in parallel spaced relation in said slits transversely of the casing with the ends of said plates arranged between the ears and providing a straight line discharge orifice; means coating with said ears and with the ends of said plates whereby the wall of the casing is drawn into snug relation with said plates and the latter removably held in place; and means in the casing whereby a turbulence in the sand-stream passing through the casing is produced.

2. A sand blast nozzle of the character described comprising a cylindrical casing having a sand and air inlet at one end and a discharge at the opposite end, the discharge end being collapsed to provide two gradually tapering walls and outwardly flared spaced apart portions between the tapered walls; flat plates arranged in parallel spaced relation between said flared spaced apart wall portions of the casing to provide a straight line discharge orifice, said plates extending into the nozzle so as to provide sand arresting pockets intermediate of the plates and the sloping wall portions of the casing adapted to receive the sand in advance of its discharge; means whereby the plates are held in place and removably secured to the casing; and means concentrically arranged in the casing intermediate of its ends and adapted to intercept the incoming sand.

3. A sand blast nozzle of the character described comprising a cylindrical casing with an air and sand inlet at one end and a discharge at the opposite end; a pair of spaced apart parallel plates at the discharge end of the casing arranged to provide a narrow elongated outlet nozzle; means whereby said plates are removably secured in place; a sand arresting element located concentrically in the casing intermediate of its ends whereby a turbulence in the sand-stream passing through the casing is provided

and finer sand produced; and means whereby water may be introduced into the casing beyond the point of discharge of said sand arresting element.

- 5 4. A sand blast nozzle of the character described comprising a cylindrical casing having a sand and air inlet at one end and a discharge at the opposite end, two opposite sides at the discharge end tapering toward each other and providing a discharge opening coextensive with the internal diameter of the casing, while the other two opposite sides of the casing are slit and formed to provide a pair of spaced apart wings on each side of the casing; matching plates arranged in the discharge end of the casing with their ends disposed between the spaced wings on opposite sides of the casing while the portions of the plates within the casing are in spaced relation with the tapering sides of the casing to provide sand arresting cavities; filler plates between the ends of the first mentioned plates to maintain the latter in prearranged spaced relation; and removable means whereby the wings and the plates are drawn into snug relation.
- 10 5. A sand blast nozzle of the character described comprising a cylindrical casing having a sand and air inlet at one end and a discharge at the opposite end, two opposite sides of the casing tapering toward each other while the other two sides flare outwardly and are slit to provide spaced apart wings, the casing interior at the flared sides being formed to provide a discharge passage coextensive with the normal
- 15 internal diameter of the casing; a pair of plates arranged in the flared end of the casing with their ends disposed between the spaced apart wings while the main portions of the plates extend into the casing in spaced relation with the tapering sides of the casing to provide tapering cavities; means whereby the plates are held in prearranged spaced relation; means whereby the plates and said first mentioned means are removably clamped between said wings; and means whereby water may be introduced into the casing intermediate of its ends.
- 20 6. A sand blast nozzle of the character described comprising an elongated casing provided with an inlet at one end and a discharge at the opposite end and having two opposite tapering sides terminating in a discharge opening coextensive with the diameter of the casing and having a pair of outwardly extending wings on each side of the casing with a slot-way therebetween; a pair of flat plates arranged in the discharge opening with their ends disposed in the slot-ways between the plates; means coacting with said wings and said plates for removably clamping the plates in place; a sand stream arresting pocket substantially at the longitudinal center of the casing intermediate of its ends; and means whereby water may be introduced in the casing at a point intermediate of the forward open end of said pocket and the discharge opening of the casing.
